UNITED STATES PATENT OFFICE.

EMILIO ROMANELLI, OF BLOOMFIELD, NEW JERSEY, ASSIGNOR TO WESTINGHOUSE LAMP COMPANY, A CORPORATION OF PENNSYLVANIA.

APPARATUS FOR HEAT TREATING METALLIC BODIES.

Application filed July 31, 1926. Serial No. 126,126.

This invention relates to a method and apparatus for treating metallic bodies and more particularly to the heat treatment of tungsten bodies employed in the manufacture of incandescent electric lamp filament.

The process of producing electric incandescent lamp filament includes the formation of bodies, termed "slugs", which are produced by compressing the tungsten powder until the particles adhere and take the form desired, usually of elongated or bar shape.

These slugs are then subjected to a heat treatment for the purpose of sintering the particles of tungsten together preparatory to a swaging and drawing operation in the production of a lamp filament. The present invention is particularly concerned with the heat treatment or sintering of the compressed tungsten bodies.

Heretofore, when a slug was to be subjected to a sintering operation it was the practice to grip each end of the slug by means of a pair of clamps. Electrical energy was then passed through the slug to raise the temperature thereof sufficient to obtain a sintering of the particles of tungsten and produce a compact homogeneous body. This manner of treatment, however, resulted in a conduction of heat from the ends of the slugs by reason of the clamps. This transfer of heat from the slug prevented a complete sintering action of such portions of the slug as were embraced by the clamps. It was, therefore, necessary to remove the incompletely sintered ends before subjecting the slug to the swaging and drawing operations, and a considerable loss in material resulted. This loss was not only undesirable from an economic standpoint, but also made it necessary to rehandle the slug for the removal of the improperly treated ends.

An object of the present invention is, therefore, to provide a method and apparatus for the more economic and convenient heat treatment of metallic bodies and to provide means for supporting a plurality of bodies during a sintering operation and to effect an automatic release of the bodies during said operation.

In accomplishing the above I provide a mercury cup for receiving one end of a slug, which has been previously sintered. To the exposed end of the sintered slug another un-

sintered slug is clamped; the two slug ends lapping each other to a width equal to the width of a slug. The upper end of the unsintered slug is secured in a spring clamp and the lapped ends of the sintered and unsintered slugs are secured between clamps which are held closed by means of a toggle joint. Electric energy is then passed through the slugs and as the unsintered slug becomes sintered it shrinks and raises the lower slug in the mercury cup. This shrinking action of the slug is utilized to actuate certain mechanical elements, which release the clamps holding the lapped ends of the slugs. This releasing action is made to occur at the proper period so that the lower slug adheres to the upper slug and the lapped ends which were previously held by the clamp obtain the full benefit of the heating current and are completely sintered.

The upper end of the slug, which was held in the spring clamp, will obviously not have been completely sintered. In the next treatment, however, the upper slug is made the lower slug and the end thereof, which has been held by the clamps and is completely sintered in position in the mercury, and the uncompletely sintered slug is held between the clamps and completely sintered upon the removal of the clamps. Thus the slugs may be fully sintered from end to end without any loss or waste.

The invention will be more fully understood by reference to the accompanying drawings in which Figure 1 is a plan view, partly broken away, of an apparatus embodying the present invention.

Figure 2 is a front elevational view of the apparatus shown in Figure 1. Figure 3 is a side view in elevation of the apparatus shown in Figure 2, but including the upper clamp for securing a slug; Figure 4 is a fragmentary detail view partly in section and shows mechanism for actuating a pair of jaws, and Figure 5 is a perspective view of a trip member for operating a pair of clamp jaws.

In the present embodiment of the invention a mercury cup 10 is suitably supported on and extends below a table or bed plate 11. Disposed at opposite sides of the mercury cup are tubular guide members 12 and 13, the lower ends of which may be suitably secured in the bed plate 11. Each guide is provided

with an internal conductor 14, through which a cooling liquid may pass into the upper end of the guide and downwardly along the interior surface thereof to maintain the guide 5 at a suitably low temperature. Each guide is provided with a slideable carrier 15 which is secured to a plate 16 by bolts 17, passing through lugs 18 on the carriers and through jaw members of oppositely disposed pairs of 10 jaws, said pairs being indicated as a whole by the numeral 19, the bolts 17 serving as pivot points for the jaws. One pair of jaws is disposed on each side of the mercury cup, and a description of one pair will serve for 15 both.

The jaws are preferably made flexible so that they may give slightly and firmly grip the objects to be secured thereby.

Each jaw comprises a pair of oppositely 20 disposed lever members 21 and 22, connected at their upper ends by cross-pieces or contact members 23. The lower ends 24 of the jaws are connected by toggles 25, the links of which are pivoted at 26 on pins 27 secured in a movable portion 30 of the carrier 25 15, the function of which will be later described. The pins 27 project into slots 28 in the plates 16. The toggles 25 may be constructed in the usual manner of the pair of links, link 29 being, however, extended and provided with a hand lever 31. This hand 30 20 lever as shown in Figure 1 is of bow shape and extends around the mercury cup and is connected to a link of each of the toggles so that an upward movement of the hand lever 35 25 may be effected to either break the toggles and open the jaws by separating the contact members 23 or a downward movement of the hand lever will operate to straighten the toggles and close the jaws.

The mechanism so far described takes care of the manual operation of the device to open or close the jaws and it will thus be evident that a sintered tungsten slug 32 may be 45 lapped at 33 with an unsintered tungsten slug 34 and secured by the jaws.

The upper end of the unsintered slug may be secured by jaws 35 and 36, jaw 35 being urged toward the jaw 36 by reason of a spring 50 member 37 carried on a projection 38 at the end of an upright 39. Electrical energy may be passed through the upright thence through the tungsten slugs by suitable conductors 30' and 30'' the mercury 31' in which 55 the lower slug 32 is disposed acting as the lower contact.

As above mentioned, the present method of treating or sintering tungsten bodies includes the use of a sintered body in connection with 60 a unsintered body and when two such bodies are clamped together and the sintering current passed therethrough the unsintered body becomes attached to the sintered body and the clamps, holding the lapped ends of the slugs may be removed by an actuation of

the hand lever 31. It is desirable, however, to automatically effect a release of the clamps and for this purpose I utilize the shrinking which occurs during the sintering of a heat treated body.

The automatic actuation of the pairs of clamping jaws 19 is attained by providing the carriers 15 with the movable ends or collars 30 in which pins 27 of the toggles are secured. These ends or collars are normally urged 75 downwardly by helical springs 42, disposed within the carriers 15 thus the action is to open the jaws.

When a pair of slugs is secured by the jaws a movement of the lever 31 causes the links 80 of the toggles to become engaged by latch members 43, pivoted at 44 on the main portion of the carrier 15. The latch members 43 are somewhat similar in form to bell cranks (see Fig. 5) but are constructed to embrace 85 the carrier members 15. Ends 45 of the latch members are disposed above projections 46 integral with the carrier members 15 and springs 47 act to normally position the latch members for engagement with the 90 toggles.

When the slug 34 shrinks the entire jaw operating mechanism moves upwardly until the ends 45 of the latch members engage the 95 stops 48 suitably positioned on posts 49.

When the latch members engage the stops the jaws will move from engagement with the lapped ends of the slugs. The slugs will, however, remain connected and a completion of the sintering action is attained. 100 The slugs are then broken apart and the upper slug is used as the lower slug in connection with the sintering operation next performed.

In view of the above it will be evident that 105 a great saving is attained which, when taken in connection with the handling of such material as tungsten affords appreciable saving varying from 2½% to 10%. By reason of the present device the operation of producing tungsten filament wire is greatly simplified and a decided advance step is attained 110 in the art. If desirable, suitable means may be provided within the mercury cup to compensate for the weight of the slugs as it 115 sinters as well as the weight of the clamps. This may be obtained by suitable springs or floats within the mercury well.

Although a preferred embodiment of the invention is shown described herein, it is 120 to be understood that modifications may be made therein without departing from the spirit and scope of the invention as set forth in the appended claims.

What is claimed is:

1. A machine for supporting metallic bars during a heat treatment which comprises gripping means for securing a plurality of bars, means for heating the bars to join them together, means for releasing the gripping 130

- means after a predetermined stage in the heat treatment sufficient to join said bars and means for continuing the heat treatment.
2. A device for sintering slugs of compressed metallic powder which comprises means for securing an end of one slug, gripping means for securing the opposite end of said slug in contact with an end of another slug, means for passing an electric sintering current through said slugs, means for releasing said gripping members after a given degree of sintering has occurred said current operating to permit a complete sintering action of at least one slug.
- 15 3. A device for sintering bodies formed of compressed metallic powder by the passage of an electrical current therethrough which comprises means for holding one body, jaws for holding another body in contact with the said first mentioned body, means for passing a sintering current through said bodies until they become joined through the said sintering action, means for actuating said jaws after said bodies have become joined and means for completing the sintering of one of said bodies.
- 20 4. A device of the class described comprising a clamp for holding a body, a mercury pool, gripping members for holding another body with one end in said pool and the other end in contact with said first mentioned body, means for holding the gripping members closed and means for releasing said members upon a contraction of at least one of said bodies.
- 25 5. A device of the class described comprising a clamp for holding a body, a mercury pool, gripping members for holding another body with one end in said pool and the other end in contact with said first mentioned body, a latch for holding the gripping members closed and means for automatically actuating said latch to release said members upon a contraction of at least one of said bodies.
- 30 6. A device of the class described, comprising a clamp for holding a body, and an electrical conductive medium, gripping jaws for holding an end of a second body in lapped contact with said first mentioned body, said second body having an end disposed in said medium, a toggle member for holding said jaws closed, means for passing an electrical sintering current through said bodies to
- sinter the same and join the contacting surfaces thereof and means for breaking said toggle to open said jaws after said bodies have become joined.
- 35 7. A device of the class described, comprising a clamp for holding a body, and an electrical conductive medium, gripping jaws for holding an end of a second body in lapped contact with said first mentioned body, said second body having an end disposed in said medium, a toggle member for holding said jaws closed, means for passing an electrical sintering current through said bodies to sinter the same and join the contacting surfaces thereof and means for breaking said toggle to open said jaws after said bodies have become joined, said current operating to completely sinter at least one of said bodies.
- 40 8. A device for heat treating bodies comprising means for gripping a body at an end thereof, jaw members for holding an end of another body in overlapped relation to an end of said supported body, means for heat treating said bodies, and means for automatically actuating said jaw members after heating said bodies to a predetermined degree, said heat treating means operating to continue the heat treatment of said bodies.
- 45 9. A device for heat treating bodies comprising means for gripping a body at an end thereof, jaw members for holding an end of another body in overlapped relation to an end of said supported body, means for heat treating said bodies, and means controlled by a predetermined change in the physical dimensions of said bodies through heat treatment to actuate said jaw members to release the overlapped ends of said bodies, said heat treating means operating to continue the heat treatment.
- 50 10. A device for supporting a pair of bars during a heat treating operation comprising gripping means for holding ends of said bars in overlapping relation, means for securing the free end of one of said bars, means for heat treating said bars and means whereby a change in the dimension of at least one of said bars actuates said gripping means to release the bars, said heat treating means operating to continue the heat treatment.

In testimony whereof, I have hereunto subscribed my name this 30th day of July, 1926.

EMILIO ROMANELLI.
